UNITED STATES PATENT OFFICE

ROBERT E. NEWELL, OF IRWIN, PENNSYLVANIA

REGULATOR

Application filed January 15, 1930. Serial No. 420,967.

The present invention relates broadly to the art of temperature regulators, and more particularly to regulators suitable for house-furnaces, boilers, and the like, although the utility of the invention is not limited with respect to the particular apparatus which it is used to control.

It is customary in the art of controlling furnaces, for example, to provide a temperature responsive element, sometimes in the form of an expandable and collapsible bellows, which cooperates with a counter-weighted lever or arm. This arm is in turn utilized for effecting the desired operation of the drafts and check valves or of the fuel control means, depending upon the type of furnace with which the control is utilized. When an adjustment is desired with such an installation, the counter-weight is moved in one direction or the other, the counter-weight normally working against the internal pressure of the bellows or other suitable means. The size of such weight, or the force required to adjust the stiff springs which are otherwise employed, renders impractical the use of a delicate control means of any type suitable for easy operation or operation from a remote point.

Furthermore, inasmuch as regulators of the type referred to are frequently placed at the top of boilers or furnaces in dark basements or boiler rooms, their adjustment is either neglected or imperfectly effected, partly because of inaccessibility and partly because of the clumsy method of adjustment which is involved.

In accordance with the present invention, there is provided an improved type of regulator suitable for control either at the furnace itself or from a remote point, as may be desired.

The construction herein disclosed by means of which the desired regulation is accomplished also embodies several advantageous features of construction and operation which will be hereinafter more fully pointed out.

In the accompanying drawing, I have shown for purposes of illustration only, a preferred embodiment of my invention.

50 In the drawing:—

Figure 1 is a view, partly in vertical section and partly in elevation, illustrating one embodiment of my invention.

Figure 2 is a front elevational view of the structure illustrated in Figure 1, and

Figure 3 is a more or less diagrammatic view illustrating a safety means incorporated in the construction.

In carrying out the present invention there may be provided a face plate or front panel 60 2, upon which are mounted the operating parts of the regulator, and by means of which the entire regulator is secured to the side wall 3 of the furnace or boiler it is desired to control.

It is preferable that this panel 2 be of material having low heat conducting and radiating qualities, the object being to prevent the operating parts of the regulator being so affected. A laminated bakelite sheet, for instance, meets this requirement, having also the necessary mechanical strength and being attractive in appearance.

Carried by the front panel by any suitable supporting means, herein illustrated as comprising a plurality of posts 4, is a temperature responsive means 5 herein illustrated as comprising an expandable metal bellows assembly or the like. This temperature responsive assembly is illustrated in Figure 1 in 80 its fully contracted position, and in Figure 3 in its fully expanded position.

Secured to the movable portion of the assembly 5 and projecting forwardly through a suitable opening in the panel 2 is an extension 6. The extreme outer end of the extension 6 is slotted or bifurcated to provide bearing portions 7 spaced a sufficient distance to receive therebetween an operating lever 8. This operating lever has a pivotal mounting 9 in a bracket 10 secured to the panel 2. For operating the lever 8 in accordance with different temperature conditions, the extension 6 carries a pivot pin 11 extending through the bearing portions 7 and 90 through the operating lever. Due to this construction, it will be apparent that as the bellows 5 expands, the operating lever is rocked in a clockwise direction about its pivot 9, while as the bellows contracts, the op- 100

erating lever moves in the opposite direction.

For assisting in guiding the lever and causing it to remain at all times in the desired position, there may be secured to the panel 2 suitable guides 12 spaced to lie on opposite sides of the lever.

At its outer end the operating lever may be shaped, as clearly shown in Figure 1, to provide oppositely projecting hook shaped portions 13 and 14. The hook 13 is adapted in the normal operation of the device to carry a ring 15 from which extends a chain or operating cable 17, secured to the front draft damper, in case of a hot air furnace, or to some other part the control of which is desired, in case of another type of installation. Cooperating with the hook 14 is a ring 18 from which extends a chain or operating cable 19 which, in the case of a hot air furnace, is secured to the rear check damper. Each of these rings also has secured thereto a retaining chain 20 so that the rings may be removed from their respective hooks at the will of the operator and the furnace manually controlled, the retaining chains holding the chains 17 and 19 together with the rings in such position that they are readily accessible for re-engagement with the hooks 13 and 14.

A disengagement of the character referred to is desirable, for example, in mild weather wherein it may be desired not to even maintain a temperature as high as the minimum temperature for which the temperature responsive means 5 is adjusted.

A further object in temporarily disengaging the operating lever 8 is to permit closing simultaneously of both front draft and rear check damper of the furnace when fueling with bituminous coal. The closing of both dampers prevents smoking at the coal door.

Formed in the panel 2 is an opening 21 with which cooperates a shutter 22, the shutter having a pivotal mounting 23. This shutter in Figure 1 is shown in closed position, while in Figure 3 it is illustrated as in its open position. The shutter is of such dimensions as to substantially conform to the opening in a casing 24 projecting rearwardly from the panel and inclosing the temperature responsive assembly 5. This casing is freely open at its upper and lower ends so as to permit the heated air to pass readily over the temperature responsive means.

With the shutter 22 in its closed position illustrated in Figure 1, it will be apparent that the only temperature to which the temperature responsive means 5 is subjected, is the temperature of the heated atmosphere within the casing. On the other hand, if the shutter 22 is moved to its partially open position, as illustrated, for example, in dotted lines in Figure 1, the temperature conditions to which the assembly 5 will be subjected will be a compromise between the temperature of

the heated air and the temperature of the outside air admitted through the opening afforded by the changed position of the shutter.

For adjusting the shutter, there may be provided an adjusting screw 25 extending through an adjusting screw plate 26 carried by the panel, the adjusting screw being effective on the shutter at a point above the plane of the pivot 23. Thus, as the screw 25 is turned inwardly, the shutter is moved to its open position against the action of a return spring 27, while as the screw is turned in the opposite direction the spring 27 is effective for returning the shutter to its closed position.

Carried by the shutter is an indicating plate 28 having suitable indicia 29 thereon adapted to cooperate with the indicator or pointer 30.

With all of the parts in the position illustrated in Figure 1, and assuming the temperature responsive assembly 5 to have been charged for complete expansion at a temperature of 135°, it will be apparent that when the heated air which surrounds the same reaches this temperature, the parts will have been moved to the position illustrated in Figure 3. In this position the chain 19 will have opened the rear check damper, while the chain 17 will have closed the front draft damper, thereby tending to cut down the rate of combustion within the furnace.

With this same charge, however, the furnace temperature at which complete expansion of the bellows takes place may be varied over wide limits by adjusting the position of the shutter. It will be apparent that as the shutter is more widely opened, more cool air will be drawn inwardly over the temperature responsive assembly from the room in which the furnace is located, so that even if the furnace is operating in such manner as to provide a supply of heated air at a temperature of 135°, the actual temperature to which the temperature responsive assembly is subjected will be a compromise between such temperature and room temperature. It may be assumed by way of example only that this compromise will subject it to a temperature of 100°. Thus, in order to obtain complete expansion of the bellows, it will be necessary for the air within the furnace to be actually heated to a higher temperature. Any desired condition from minimum to maximum temperature conditions may be obtained by suitable adjustment of the shutter 22.

Not only does this provide an accurate type of control of temperature conditions, but it prolongs the life of the apparatus itself since the temperature responsive means is never subjected to a temperature as high as the maximum air temperature. This tends to considerably prolong its length of life.

As a safety means, I may provide the op-

erating lever 8 with an extension 31 so disposed that when the bellows has expanded to a predetermined point, the lower end of the extension 31 will come into engagement 5 with a safety trigger pin 32 projecting forwardly from the shutter. After this engagement, continued movement of the lever 8 in a clockwise direction will be effective for swinging the shutter 22 to its open position 10 and thereby admitting a large volume of relatively cold air to the system.

Because of its simplicity and ease of adjustment by delicate means, it will be apparent to those skilled in the art, that any 15 desired movement of the shutter 22 may be effected from a remote point in various ways, as for instance, by means of light flexible cables or tubes transmitting pressure, etc., said cables or pressures being actuated either 20 manually or thermostatically at a remote point.

The device also lends itself admirably to electrically operated remote control, such for example, as that ordinarily referred to as 25 room temperature control. This may be accomplished by positioning within the assembly 5 a resistance heating element 33, which may be of any desired construction, and the terminal wires of which come 30 respectively to connections 34 and 35. By providing a temperature responsive switch in a room at a position remote from the regulator effective for closing the circuit when the temperature in a room rises, current may 35 be supplied to the heating unit 33 for expanding the bellows irrespective of the temperature of the air in the furnace. In this manner the regulator may be made responsive not only to air temperature, but also to 40 room temperature.

While I have herein illustrated a construction in which the lever 8 is shown as effective for operating dampers, it will be understood 45 that it is equally effective for operating other devices, such as valves and the like. It may also be utilized either directly, or through the medium of chains as illustrated, for opening or closing other electric circuits 50 such as those which control fans, blowers, or the like constituting a part of the circulatory system for the heated air.

From the foregoing it will be apparent 55 that I have provided a relatively simple and compact device which may be easily installed in a furnace in such manner as to effectively control the fire conditions therein. It also embodies means whereby a combined control such as that represented both by air temperature and room temperature may be simultaneously obtained.

The construction illustrated also obviates 60 the use of cumbersome weights or of relatively stiff springs, and provides a construction which is compact, easily operated and easily installed.

While I have herein illustrated certain preferred embodiments of my invention, it will be understood that changes in the construction and operation described herein may be made without departing either from the 70 spirit of the invention or the scope of my broader claims.

I claim:

1. In a temperature regulator, a casing, 75 temperature responsive means in said casing, said casing being constructed for the flow therethrough of a heating medium, and means for varying the effectiveness of such medium, said means including a manually operable control valve for admitting another 80 medium at different temperature thereto, there being means normally out of operative engagement with said valve for automatically moving said valve when said temperature responsive means reaches a predetermined 85 temperature.

2. In combination, a furnace regulator, a wall forming a confining means for a heated medium, a casing carried by said wall, an 90 expansible and collapsible element within said casing, and connections for delivering heating medium from a plurality of sources to said casing, one of said connections communicating with the space within said wall.

3. In combination, a furnace regulator, a 95 wall forming a confining means for a heated medium, a temperature responsive means, a casing carried by said wall and partially enclosing said means and adapted to have supplied thereto heat from a plurality of different sources, one of which includes the space within said wall, and remote control means 100 for decreasing the amount of heat from one of said sources.

4. In combination, a furnace regulator, 105 a wall forming a confining means for a heated medium, a temperature responsive means, a casing carried by said wall and partially inclosing said means and adapted to have supplied thereto a plurality of fluids 110 of different temperature, means for decreasing the amount of one of said fluids and increasing the amount of the other, said means including a manually adjustable control valve, and temperature responsive means for 115 moving said valve.

5. The combination with a furnace, of a 120 temperature regulator, said regulator including a temperature responsive manually adjustable means bodily disposed within the furnace, and means for more or less shielding said temperature responsive means from the temperature within the furnace and subjecting said temperature responsive means to compromise temperature conditions different 125 from those existing within the furnace.

6. The combination with a furnace, of a 130 temperature regulator, said regulator including a temperature responsive means bodily disposed within the furnace, and means for

- more or less shielding said temperature responsive means from the temperature within the furnace and subjecting said temperature responsive means to compromise temperature responsive means different from those existing within the furnace, said last mentioned means including a manually adjustable valve for admitting to said temperature responsive means relatively cool air from a point exteriorly from the furnace.
10. 7. In a furnace regulator, a damper operating lever, damper operating connections secured thereto, temperature responsive means for operating said lever, and means operated by said lever for substantially cutting off the supply of heat thereto from the furnace and permitting the passage to said temperature responsive means of a relatively cool actuating medium.
15. 8. In a furnace regulator, a damper operating lever, damper operating connections secured thereto, temperature responsive means for operating said lever, and means operated by said lever for substantially cutting off the supply of heat thereto from the furnace and permitting the passage to said temperature responsive means of a relatively cool actuating medium, said means including a valve operable by said lever when the lever is in predetermined position.
20. 9. A temperature regulator, comprising a support having an opening therein, a casing having inlet and outlet openings, heat responsive means within said casing, said casing being effective for shielding the heat responsive means from a source of heat, and a valve for opening or closing said first mentioned opening and simultaneously closing or opening said inlet opening for varying the effectiveness of said heat source on said heat responsive means.
25. 10. A temperature regulator, comprising a support having an opening therein, a casing having inlet and outlet openings, heat responsive means within said casing, and a valve for opening or closing said first mentioned opening and simultaneously closing or opening said inlet opening, said valve being mounted to swing across said casing.
30. 11. A temperature regulator, comprising a support having an opening therein, a casing having inlet and outlet openings, heat responsive means positioned within said casing, and a valve for opening or closing said first mentioned opening and simultaneously closing or opening said inlet opening.
35. 12. A temperature regulator, comprising a support having an opening therein, a casing having inlet and outlet openings, heat responsive means positioned within said casing, and a valve for opening or closing said first mentioned opening and simultaneously closing or opening said inlet opening, said valve being adapted to swing across said casing.
40. 13. A temperature regulator, comprising a support having an opening therein, a casing having inlet and outlet openings, heat responsive means within said casing, and a valve for opening or closing said first mentioned opening and simultaneously closing or opening said inlet opening, there being means for manually or automatically operating said valve.
45. 14. A temperature regulator, comprising a support having an opening therein, an open ended casing with one end serving as an inlet and the other end as an outlet opening for the casing, heat responsive means positioned within said casing intermediate said open ends, and a valve carried by said support for opening or closing said first mentioned opening and simultaneously closing or opening said inlet opening, there being means for manually or automatically operating said valve.
50. 15. A temperature regulator, comprising a support having an opening therein, a casing having inlet and outlet openings, heat responsive means within said casing, and a valve for opening or closing said first mentioned opening and simultaneously closing or opening said inlet opening, there being connections between said heat responsive means and said valve whereby the valve may be automatically moved by said heat responsive means.
55. 16. A temperature regulator, comprising a support having an opening therein, a casing having an open inlet end and an open outlet end, heat responsive means positioned within said casing intermediate said open ends, and a valve for opening or closing said first mentioned opening and simultaneously closing or opening said inlet end, there being connections between said heat responsive means and said valve whereby the valve may be automatically moved by said heat responsive means.
60. 17. The combination with a furnace wall having an opening therein, of a cover for said opening also having an opening therein, a casing within said wall adjacent said first mentioned opening and provided with inlet and outlet openings, heat responsive means in said casing, and a control valve for said cover opening carried by said cover.
65. 18. The combination with a furnace wall having an opening therein, of a cover for said opening also having an opening therein, a casing within said wall adjacent said first mentioned opening and provided with inlet and outlet openings, heat responsive means in said casing, and a control valve for said cover opening carried by said cover, said control valve being operative for closing or opening said cover opening and simultaneously enlarging or restricting the inlet opening of said casing.
70. 19. The combination with a furnace wall

having an opening therein, of a cover for said opening also having an opening therein, an open ended casing within said wall adjacent said first mentioned opening and 5 carried by said cover, heat responsive means in said casing adjacent one end thereof, and a control valve for the opposite end of said casing.

20. The combination with a furnace wall 10 having an opening therein, of a cover for said opening also having an opening therein, an open ended casing within said wall adjacent said first mentioned opening and carried by said cover, heat responsive means 15 in said casing adjacent one end thereof, and a control valve for the opposite end of said casing, said control valve being operable for restricting or enlarging the effective opening of one end of the casing of said casing 20 and simultaneously opening or closing said cover opening.

21. In a regulator, a temperature responsive means adapted for primary control by a temperature controlling medium, and a 25 plurality of means for varying the effectiveness of such medium, one of said means including means for artificially supplying heat from a source other than said medium to the temperature responsive means, and another 30 of said means including mechanism for shielding said temperature responsive means from said medium in whole or in part.

In testimony whereof I have hereunto set
my hand.

35 ROBERT E. NEWELL.
